MATTRESS

Filed March 16, 1925.

UNITED STATES PATENT OFFICE.

LOUIS G. IHRIG, OF SAN DIEGO, CALIFORNIA, ASSIGNOR TO STANDARD MATTRESS AND FURNITURE MANUFACTURING COMPANY, OF SAN DIEGO, CALIFORNIA, A CORPORATION OF CALIFORNIA.

MATTRESS.

Application filed March 16, 1925. Serial No. 15,871.

My invention relates to mattresses and the objects of my invention are: First, to provide a mattress structure in which the usual stretching, both longitudinally and laterally, when in use, will be eliminated or reduced to a minimum; second, to provide a mattress in which the resiliency of the material used in stuffing the mattress will be retained to a great extent and to a larger extent than in the conventional mattresses; third, to provide a mattress, which by reason of opposed tufts and tufted pockets, provides a very soft and resilient mattress structure; fourth, to provide a mattress which is capable of being easily ventilated on the inside; fifth, to provide a mattress which can be made to suit individual needs and applicable for winter and summer use by providing different kinds of stuffing at the opposite sides of the mattress; sixth, to provide as a whole a novelly constructed mattress, and seventh, to provide a mattress of this class which is simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, in which:

Figure 1 is a perspective view of my mattress, showing the one end thereof cut away and in section to facilitate the illustration, and Fig. 2 is another perspective view of a fragmentary portion of my mattress in a slightly modified form of construction, showing the cut portions in section.

Like characters of reference refer to similar parts and portions throughout the views of the drawings.

In the preferred embodiment of my invention, as illustrated in the drawings, my mattress consists of two substantially identical mattress sections A and B secured together at their adjacent edges. Each section of the mattress is encased in a baglike fabric tick 1. The one or normally outer side 1^a of each tick is made of substantially the size of

the completed mattress, while the normally inner or adjacent sides of said ticks are made considerably longer and wider than the finished size of the mattress, as indicated by dotted lines C in the drawings. In the ticks 1 is provided a suitable stuffing 2, as will be described later. After the stuffing is positioned in the ticks, the larger inner sides 1^b of the ticks are sewed to the smaller outer sides 1^a by means of the stitching twine 3. The outer sides of the mattress being held flat and the inner larger sides of the tick 1^b being sewed to the former, will permit the inner side of the tick to assume a tufted shape, while the outer side of the tick will remain flat or plane.

This construction of the mattress sections will not permit the mattress to stretch any appreciable degree, as is usual in the mattresses now in use particularly after long and hard wear.

The outer edges or corners 1^c of the mattress sections are sewed in bead form by the stitching 4, as in the conventional construction. The adjacent edges of the tufted adjacent sides 1^b of the tick are sewed to form flaps 1^d or sewing edges. The adjacent flaps or sewing edges 1^d of the two mattress sections A and B are sewed together by the stitching 5 forming a mattress having flat upper and lower sides with tufted engaging inner sides and air pockets between the tufted portions.

To the beads 1^c at the side edges of the mattress sections are sewed the edges of a box edge member 6 which extends completely around the edge of the mattress and conceals the stitching connecting the separate mattress sections. Intermediate the edges of the box edge member or strip 6 is secured a plurality of ventilating eyelets 7 for permitting air to enter the pockets between the tufted portions of the mattress sections and also to be discharged therefrom.

A mattress constructed as shown and described may be conveniently made to suit individual needs depending upon the person and also climatic conditions; for instance, by stuffing the section A with hair, said section would be desirable for a fat person or applicable for summer use, while the section B stuffed with kapok and the mattress

turned upside down would be desirable for elderly or thin blooded people and applicable for winter use.

- In the modified form of construction, shown in Fig. 2 of the drawings, I have provided straps 8, made of fabric or any other suitable material, which are sewed at intervals, either longitudinally or laterally, to the insides of the outer sides 1^a of the tick 1.
- 10 When sewing the larger inner sides 1^b of the tick to the outer sides 1^a, the stitching twine 3 is sewed through the straps 8 and the outer sides 1^a of the ticks, then back through the same hole in the tick and through another portion of the strap 8. Thus the opposite sides of the tick are sewed together without showing stitching at the outer sides of the mattress.

Though I have shown and described a particular construction, combination and arrangement of parts and portions and a certain modification thereof, I do not wish to be limited to this particular construction, combination and arrangement nor to the modification, but desire to include in the scope of my invention the construction, combination and arrangement substantially as set forth in the appended claims.

Having thus described my invention, what

I claim as new and desire to secure by Letters Patent is:

1. A mattress, comprising a pair of mattress sections, the one superposed upon the other, the outer sides of said sections forming the top and bottom of the mattress being relatively flat and smooth, and the inner sides of said sections lying adjacent each other being tufted forming oppositely disposed cushions and air pockets, and a box edge strip surrounding the side edges of said mattress sections forming in appearance a one section mattress.

2. A mattress, comprising a pair of mattress sections, the one superposed upon the other, the outer sides of said sections forming the top and bottom of the mattress being relatively flat and smooth, and the inner sides of said sections lying adjacent each other being tufted forming oppositely disposed cushions and air pockets, and a perforated box edge strip surrounding the side edges of said mattress sections forming in appearance a one section mattress.

In testimony whereof, I have hereunto set my hand at San Diego, California, this 9th day of March, 1925.

LOUIS G. IHRIG.
